UNITED STATES PATENT OFFICE.

FRIEDRICH W. HERINGSHAUSEN, OF NEW YORK, N. Y.

SOFA.

SPECIFICATION forming part of Letters Patent No. 397,800, dated February 12, 1889.

Application filed May 24, 1888. Serial No. 274,980. (No model.)

To all whom it may concern:

Be it known that I, FRIEDRICH W. HERINGSHAUSEN, a citizen of the United States, residing at New York, in the county and State of 5 New York, have invented new and useful Improvements in Sofas, of which the following is a specification.

This invention relates to an improvement in sofas by which a head-rest can be conveniently placed at varying angles, as set forth in 10 the following specification and claims, and illustrated in the accompanying drawings, in which—

Figure 1 is a front view of a sofa. Fig. 2 15 is a longitudinal sectional view with parts in a different position. Fig. 3 is a section in the plane xx , Fig. 1; and Fig. 4, a detail sectional view of the movable back-section and its depending extension.

20 Similar letters indicate corresponding parts.

In the drawings, the letter A indicates a seat-frame, and B is a back. The foot-section C is shown movable about a pin or support, D. When the hook E is released, the foot-section C can be swung to the position shown 25 in Fig. 2.

The head piece or section F is shown movable about pivot-pins G, mounted in fixed parts G' of the frame. Said head-section has 30 a back-section, H, forming a continuation of the back B, and provided with an extension, I, which depends downward through a longitudinal recess or slot, I', at the rear of the sofa-seat, and has the extremity toward the 35 foot-section C formed into a segmental projecting edge, which fits a corresponding segmental cavity formed in the adjacent edge of the rigid back B. The extension I is rigidly secured to the inside of the back-section H, 40 as seen in Fig. 4, and projects laterally therefrom, so that it is brought toward the sofa-seat and can run in the recess or slot in the seat-frame, while at the same time its inner face is flush, or substantially so, with the inner faces of the back-sections H and B, in such manner that even when the head and back sections F and H are tilted to their extreme positions, as in Fig. 2, there will be no 45 gap between the head-section H and back B; but, on the contrary, the continuity of the en-

tire back is preserved. The extension I is firmly guided and steadied by the seat-frame. In Fig. 3 is indicated the relative positions of the seat-frame A and the extension I, and the said extension is shown by dotted lines as 55 passing through the recess or slot I' in the seat-frame. By attaching the extension I to the inside of the back-section, so that the extension projects laterally inward toward the sofa-seat, there is provided space whereby the 60 section H and back B can be upholstered, so that the upholstering will be substantially flush with the inner surface of the extension I. The extension need not necessarily be upholstered, but it may be covered with cloth, 65 if desired. The width of the slot or recess I is obviously sufficiently wide relatively to the thickness of the extension I as to permit the latter to freely move. When the head-section is swung to the position shown in Fig. 2, 70 the extension I will prevent the continuity of the back from being broken, so that when said head-section is placed at varying angles the back of the sofa will always be closed or unbroken.

75 The teeth K are adapted to be engaged by a catch, L, and by causing said catch to engage one or another of the teeth K the head-section will come to rest at various angles, as desired. A button or head, M, enables the 80 catch L to be thrown out of engagement with the teeth K, and a spring, N, holds said catch in engagement with a tooth, K.

85 What I claim as new, and desire to secure by Letters Patent, is—

1. A sofa consisting of the seat A, having a longitudinal slot or recess, I', at its head, a sofa-back, B, provided with a segmental cavity in its edge nearest the sofa-head, and an adjustable pivoted head, F, having a rigid back-piece, H, provided at its base with an extension, I, offset at the front of said rigid back-piece to be substantially flush with the upholstering thereupon depending downward through the longitudinal slot or recess in the sofa-seat, and having a segmental projecting edge fitting the segmental cavity in the adjacent edge of the sofa-back, substantially as described.

95 2. A sofa consisting of the seat A, having a 100

sofa-back, B, and a longitudinal slot or recess, I', near its head, and a pivoted head, F, having a rigid back-piece, H, and an extension, I, offset in front of said rigid back-piece to be
5 substantially flush with the upholstering thereupon and depending downward through the longitudinal slot or recess in the sofa-seat when the pivoted head is swung back, substantially as described.

In testimony whereof I have hereunto set my hand and seal in the presence of two subscribing witnesses.

F. W. HERINGSHAUSEN. [L. S.]
